UNITED STATES PATENT OFFICE

EUGENE C. HEILHECKER, OF BRISTOL, RHODE ISLAND, ASSIGNOR TO NATIONAL INDIA RUBBER COMPANY, OF BRISTOL, RHODE ISLAND, A CORPORATION OF RHODE ISLAND

FOOTWEAR

Application filed November 12, 1930. Serial No. 495,058.

This invention relates to footwear and more particularly to that type of shoe having an upper usually of canvas provided with a lace-to-toe opening and used for sport or 5 athletic wear.

In former shoes of this type the quarters terminated short of the toe portion of the shoe, which portion was formed by an extension of the tongue. The tongue of the shoe 10 was edged with a bias binding extending downward on the interior of the shoe adjacent the toes of the wearer's foot and followed the general contour of an eyelet stay or reinforcing strip. One serious objection 15 to this type of shoe is that when the same is laced onto the foot there is considerable bunching of the material of the upper adjacent the toe portion which causes chafing of the binding of the tongue against the wearer's 20 toes. This was one of the chief objections to wearing a lace-to-toe pattern shoe for basket ball and other kinds of exercise.

One of the objects of the present invention is to overcome the above noted objections. 25 For this purpose the quarters of the shoe are extended forward to form the toe portion of the shoe, and the tongue is connected adjacent the rear edge of the toe portion above the sides of the wearer's toes, as contrasted 30 with former practice wherein the tongue formed the toe covering portion. Preferably the eyelet stay is extended downward to the sole as in former shoes of this general type, so that while the shoe presents substantially the same outward appearance as 35 formerly, it is nevertheless of radically different construction on the interior since it is entirely free of the objectionable edges or bindings which caused chafing heretofore.

40 Various other objects and advantages of the present invention will appear as the description proceeds. In the accompanying drawings forming a part of this specification—

45 Figure 1 is a side elevation of a shoe incorporating the invention and having portions broken away to show the interior construction;

50 Fig. 2 is a cross section on the line 2—2 of Fig. 1;

Fig. 3 is a plan view of the outside of an upper embodying the invention;

Fig. 4 is a view of parts which enter into the construction of the upper disclosed in Fig. 3; and

Fig. 5 is an underneath view of the toe region of the upper shown in Fig. 3.

In the accompanying drawings the reference numeral 10 indicates an upper, the quarters of which are preferably made in two sections or side members 11 and 12 having forward extensions 13 and 14 respectively, joined together along a median line 15 to form a toe covering portion. The two sections 11 and 12 may comprise an outside 60 fabric 16 consisting of canvas, and a suitable lining 17. The outside fabric 16 and the lining 17 are preferably of the contour shown in Fig. 4 and may be cemented together to form in effect one fabric or they may be built into 65 the shoe as separate pieces. In building the shoe of the present invention the margins of two parts 11 and 12 preferably are butted together along the median line 15 and held together in any suitable way such as by the 70 stitches 18, and a pair of eyelet stays 19 are stitched to the sides of the shoe opening formed by the edges 19' to a point within about one-half inch of the bottom of a tongue 75 20 which is put into position between a pair of notches 21 adjacent the rear of the toe covering portions 13 and 14, the bottom of the tongue preferably overlapping the outside 80 of said portions as indicated in Fig. 3. The lower portion 22 of the tongue is stitched 85 down, preferably as indicated at 23, to the extensions 13 and 14 of the sections 11 and 12 forwardly of the notches 21, and then the downwardly extending portions 24 of the eyelet stays 19 are stitched down to the sides of the upper. To further reinforce the connection of the tongue to the upper several lines 90 of stitching 27 may be run across the eyelet stays 19 adjacent the lower portion of the tongue 20. The upper may be provided with any suitable form of heel stiffening means 28 and may be further provided with reinforcing stays 29 at the sides of the foot. The upper thus formed is joined together at the 95 rear edges 31 in any approved manner and is 100

then lasted on to a sole which may comprise an insole 32, a filler sole 33, and an outsole 34 preferably of rubber composition. To further reinforce the toe portion of the shoe and 5 form a covering for the stitches 18, there is preferably provided a toe cap 30 of rubber composition. The toe cap 30 may be applied in any suitable manner, and usually consists of suitably compounded gum of the proper 10 thickness to reinforce the toe portion and leave no trace of the stitches 18.

It will be seen from an inspection of Figs. 1 and 3 that the lower portion 22 of the tongue 20 has no edges or shoulders extending 15 downward over the sides of the wearer's toes. This has been accomplished by providing the quarters with the integral extensions 13 and 14 which formerly were a portion of a tongue having a binding on its edges. There 20 is consequently presented a substantially smooth interior adjacent the forward part of the shoe so that when the shoe is laced onto the foot there is nothing in the toe portion to cause chafing.

25 It is to be understood in conclusion that the present described embodiment is merely illustrative of one practical embodiment of the invention, and it is therefore not intended to impose limitations other than those set forth 30 in the appended claims.

Having thus described my invention, what I claim and desire to protect by Letters Patent is:

1. A shoe having a fabric upper wherein 35 the quarters are extended forwardly to form a toe portion, said upper having a foot opening and oppositely disposed notches at the sides of said opening rearward of the toe covering portion, a tongue having its lower portion 40 extended through said notches and connected to the rear of said toe covering portion, the lower edges of said tongue terminating substantially above the areas of the upper normally engaging the wearer's toes, and re- 45 inforcing stays at the margins of said opening, said stays being extended downward over the outside of the shoe adjacent the toe portion to the sole and being secured to the tongue and the upper adjacent the lower portion 50 of said tongue.

2. A shoe having an upper including side members including portions at the front of the shoe joined together on a line approximately lengthwise of the foot and forming 55 the toe of the shoe, said upper having a foot opening, eyelet stays extending along the margins of said foot opening and downward to the sole of the shoe adjacent the toe portion, said upper having notches at the sides 60 of said opening adjacent the toe covering portion, and a tongue having its lower margins extending through said notches and connected to the rear of said toe covering portion on the outside of the upper.

65 3. A shoe having an upper including side

members including portions at the front of the shoe joined together on a line approximately lengthwise of the foot and forming the toe of the shoe, said upper having a foot opening, eyelet stays extending along the margins of said foot opening and downward to the sole of the shoe adjacent the toe portion, said upper having notches at the sides of said opening adjacent the toe covering portion, a tongue having its lower margins extending through said notches and connected to the rear of said toe covering portion on the outside of the upper, and a cap for the toe of the shoe.

Signed at Bristol, county of Bristol, State 80 of Rhode Island, this 4th day of November 1930.

EUGENE C. HEILHECKER.
